[57] CLAIM

The ornamental design for a combined interior roof lining, rear view mirror, sun visors and overhead console for an automobile, as shown and described.

DESCRIPTION

FIG. 1 is a perspective view of a combined interior roof lining, rear view mirror, sun visors and overhead console for an automobile showing our new design it being understood that the broken lines are for illustrative purposes only;

FIG. 2 is a bottom plan view thereof;

FIG. 3 is a front elevation view thereof looking in the direction of arrow 3 in FIG. 2;

FIG. 4 is a sectional view thereof taken along line 4—4 in FIG. 2;

FIG. 5 is a side and bottom perspective view thereof;

FIG. 6 is a rear and bottom perspective thereof; and

FIG. 7 is a perspective view thereof similar to that of FIG. 5 but with the sun visors in an alternate position.
